CLAIM

The ornamental design for a sleep apnea cannula and nasal pillows device, as shown and described.

DESCRIPTION

FIG. 1 is a perspective view of a sleep apnea cannula and nasal pillows device showing my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

(Continued)

The dashed broken lines in the drawings depict portions of the sleep apnea cannula and nasal pillows device that form no part of the claimed design.

1 Claim, 7 Drawing Sheets
